UNITED STATES PATENT OFFICE.

SIEGFRIED HANSING, OF NEW YORK, N. Y.

PRESSURE-BAR FOR UPRIGHT PIANOS.

SPECIFICATION forming part of Letters Patent No. 443,277, dated December 23, 1890.

Application filed October 3, 1890. Serial No. 366,955. (No model.)

To all whom it may concern:

Be it known that I, SIEGFRIED HANSING, of the city, county, and State of New York, a citizen of the German Empire, have invented 5 certain new and useful Improvements in Pressure-Bars for Upright Pianos, of which the following is a specification.

For the purpose of preventing the vibration and sounding of that part of the strings of a 10 piano which are extended beyond the string-bridge, a pressure-bar is used that is arranged between the string-bridge and tuning-pins, so that thereby the sounding portions of the strings are separated from the non-sounding 15 portions of the same. This pressure-bar is screwed down to the wrest-plank and prevents the vibrating of the ends of the strings, so that the sound of the same is made stronger and fuller. The stronger the pressure-bar is 20 pressed against the ends of the strings the more perfect is its position thereon. Heretofore the pressure-bar was attached by means of screws to the wrest-plank in such a manner that by the pressure of the pressure-bar 25 on the strings and the screws the reliable connection between the pressure-bar and wrest-plank was obtained, and thereby the vibrating of the ends of the strings beyond the string-bridge almost entirely prevented.

30 The object of my invention is to improve the connection of the pressure-bar with the string-frame in such a manner that the pressure-bar is supported in a rigid and reliable position on the strings; and the invention 35 consists of the combination, with a metallic string frame provided with raised lugs cast integral therewith, of a pressure-bar that extends over the strings, it being supported on the lugs and attached by fastening-screws to 40 the string-frame, as will be fully described hereinafter, and finally pointed out in the claims.

In the accompanying drawings, Figure 1 represents a front elevation of my improved 45 pressure-bars for upright pianos, and Figs. 2 and 3 are vertical transverse sections of the same, respectively, on lines 2 2 and 3 3, Fig. 1.

Similar letters of reference indicate corresponding parts.

Referring to the drawings, A represents the 50 string-frame of an upright piano, and B the strings, which are stretched over the sounding-board bridge C and over the string-bridge D, and which are firmly pressed down above the string-bridge by means of a pressure-bar 55 E, which is attached by screws e to the string-bridge and wrest-plank, so that the ends of the strings are tightly strained and the vibration and sounding of the same prevented. For the purpose of supporting the pressure- 60 bar E rightly in position, it is supported on lugs a a, that are cast integral with the string-frame A, said lugs having concave faces that support the convex under side of the pressure-bar E. The lugs a support the pressure- 65 bar rigidly in position and impart the required degree of stiffness to the same, so that it presses firmly on the strings and improves thereby the tone of the same and the quality of the piano.

Having thus described my invention, I 70 claim as new and desire to secure by Letters Patent—

1. The combination, with the string-frame and string-bridge of a piano, said string-frame 75 being provided with lugs that are cast integral therewith, of a pressure-bar that is supported on said lugs and extended over the strings above the string-bridge, and screws for attaching said pressure-bar to the string- 80 frame, substantially as set forth.

2. The combination, with a string-frame having lugs made integral therewith; said lugs being provided with concave faces, of a string-bridge attached to said string-frame, strings 85 stretched over the same, and a pressure-bar, having a convex under side, placed transversely across the strings above the string-bridge, and screws for attaching the pressure-bar to the string-frame, substantially as set 90 forth.

In testimony that I claim the foregoing as my invention I have signed my name in presence of two subscribing witnesses.

SIEGFRIED HANSING.
